UNITED STATES PATENT OFFICE.

CHARLES AXEL BACKSTROM, OF TRENTON, NEW JERSEY, ASSIGNOR OF ONE-HALF TO CHARLES DE BERARD SHEPARD, OF NEW YORK, N. Y.

CENTRIFUGAL CREAMER.

SPECIFICATION forming part of Letters Patent No. 355,048, dated December 28, 1886.

Application filed March 2, 1886. Serial No. 193,725. (No model.)

To all whom it may concern:

Be it known that I, CHARLES AXEL BACKSTROM, a resident of the city of Trenton, in the county of Mercer and State of New Jersey, have invented certain new and useful Improvements in Centrifugal Creamers or Separators, of which the following is a clear and exact description, and which accompanying drawings illustrate.

10 My invention relates to centrifugal machines of the class in which compound fluids or semi-liquids are separated by the action of centrifugal forces; and my improvements have for their objects to provide a machine of a novel, 15 simple, and durable construction that will perform this process more readily and more effectively than has heretofore been accomplished.

To these ends my improvements consist in certain features of construction, hereinafter 20 described, and particularly pointed out in the claims.

I supply the liquids to be separated through the receiver at the top of the separating-vessel, in which they become partly separated by 25 the action of centrifugal forces, and as the separating-vessel is filled the partly-separated ingredients of the liquid enter the coil of tubing placed at the inner periphery of the separating-vessel, where a complete separation 30 gradually takes place, all the heavier ingredients remaining in the coil, while the lighter ones are forced back into the separating-vessel through the number of pipes connected with the coil. In this way the fluids are made to 35 remain in the separating-vessel a longer time than in separators heretofore constructed, and it will be possible to accomplish a complete separation with the separating-vessel running at a speed a great deal less than heretofore 40 has been customary and necessary. The liquids after separation are discharged from the separating-vessel into a case or collector underneath the same by gravity.

In the drawings, Figure 1 is a vertical section of the separator, showing in detail the different parts composing the same and their relation to each other. Fig. 2 is a plan and cross-section at the line x x , showing location of tubing and discharge-orifices.

50 The vessel A (shown in both figures) is cylindrical horizontally and semi-elliptic vertically,

and is provided at its bottom, which is flat, with a short neck, B, down the sides of which the fluids run after separation.

Z is a driving-spindle, secured to the separating-vessel by means of rivets or in any other suitable manner.

55 C is a receiver of the liquids, through which the separating-vessel A is supplied, and is fitted centrally and partially within same, and secured to a projecting part, Z', of the spindle Z by means of a bolt, l, in such a manner that it may be readily removed when access to the separating-vessel is required.

60 t is a tube, of suitable size, secured to the receiver C, close to the bottom thereof, through which the separating-vessel A is supplied, the vessel C being made very large, so as to hold a large quantity at a time, and thus insure 65 regularity in the feeding of the separating-vessel A.

70 T is a tube of large proportions, bent to conform with the separating-vessel A, running close to the inner periphery thereof, and provided with a number of short pipes, all in connection therewith and projecting toward the center of the separating-vessel, and all reaching a point where the liquid in the separating-vessel stands permanently, or just outside of this point. The outer end of this tube T is 75 open, while the lower end, which terminates in the neck B, is closed by an adjustable screw, t'. The advantages gained by this construction are apparent. The fluids will remain in the separating-vessel a longer time, while the 80 apparatus can be of very small proportions and run at less speed than has heretofore been possible. The heavier ingredients flow through the tube T freely and entirely of their own inclination, and as the delivery takes place at 85 the bottom of the separating-vessel they will be removed therefrom by gravity and emptied in a case or collector, D, at the bottom or underneath the separating-vessel. Simultaneously with the delivery of the heavier ingredients the lighter ones will pass down the neck B, whether in the form of lumps or liquid, and will be discharged in a manner similar to that of the heavier ones, and while the former are discharged through a mouth, t', the latter will be discharged through a slot or orifice, 90 k, in the bottom of the separating-vessel.

95 100

D is a collector or condenser of the separated liquids, and is divided by plates D' D² into two or more annular compartments, D³ D⁴, as the case may require, each compartment being provided with a duct, D⁵ D⁶, and while the heavier ingredients will enter compartment D³ through the mouth t³, which is in close proximity to the partition-plate D', so as to deliver the liquid upon this plate and arrest it in its motion, the lighter ingredients will enter compartment D⁴ through an orifice or slot, k, and a small tube, k', bent in the opposite direction to that the separating-vessel is running, said tube k' closely fitting a groove or flange, d, in the extreme edge of the partition-plate D', and from which groove the lighter ingredients may run down into the case D in an unbroken state, and not in the form of a fine spray, as in separators heretofore constructed.

20 R is a frame supporting the operative parts, which frame is mounted upon three elastic supports, r' r² r³, so as to allow the machine to stand free without being secured to the floor by bolts, as has heretofore been necessary. Upon 25 this frame the case D is mounted, and secured thereto permanently.

V is a bush or bearing, secured to the frame R, in the usual manner, by means of a flexible ring, w, and a clamp, y, and this bearing simply 30 serves as a guide for the separating-vessel A in the starting of the machine, and is made large enough to allow the spindle to run perfectly free after it has found its center of rotation.

35 O is the main or driving spindle, to which motion is imparted by a belt running over a grooved pulley, f. The spindle O runs in fixed bearings or bushes, g h, fitted to pockets G H in the frame R, and is supported upon a step, L, 40 screwed into the lower part of the bush h and clamped by means of a jam-nut, r. The bushes g h are provided with linings g' h', the bushes and linings together forming oil-chambers g² h', capable of holding a large quantity of oil, 45 which is allowed gradually to escape through slots g³, cut longitudinally in the linings, said slots being filled with lamp-wick g⁴, (shown by solid black in the lower half only of one of the slots g³,) which is constantly rubbing against 50 the rotating spindle, thus insuring a perfect lubrication at all times.

The driving-pulley f is fitted to the lower part of the lining g' in bush g, on which it rotates freely. The pulley f is provided with a 55 large hub, f², which carries a pin, f', said pin driving the spindle O. This is a most important and valuable feature in my invention, as by this arrangement the spindle O is allowed to run perfectly free, and is not affected by the pull of 60 the belt sidewise, and in this manner will run for almost any length of time without perceptible wear, the strain being entirely on the lining g' and bush g. The upper end of the spindle O is formed into a socket, O', provided 65 with a conical seat, which conforms with the butt on the lower end of the upper spindle, Z,

thus the two spindles, when joined together, forming virtually but one spindle, this arrangement being made possible with the employment and aid of a driving-pulley constructed as aforescribed.

It will be apparent that in the operation of this machine all clogging and obstruction in the removal of the liquids is fully prevented, and a continuous separation may be carried on for any length of time. All passages and outlets are made very large, and the liquids are removed by gravity.

The walls of the neck are vertical to prevent the lighter liquid from moving otherwise than by gravity. If the walls of the neck were outwardly and downwardly flared, as heretofore, the cream would be shot out of the vessel and its fiber broken, which is very objectionable. By means of the neck I provide a place where I can draw off liquids at any point desired by the action of gravity alone. By extending the spindle and securing the receiving-vessel thereto, the separating-vessel as a whole is strengthened against rupture by high velocity of rotation, as sometimes occurs in this class of machines.

Having now fully described my invention, what I claim as new, and desire to secure by Letters Patent, is—

1. In a centrifugal machine, a separating-vessel, in combination with a coil having branch pipes projecting toward the center of the vessel, substantially as specified, whereby that portion of the liquid having the greater specific gravity is by centrifugal force caused to travel along in and to be discharged at the end of the coil, while that portion of the liquid having the lesser specific gravity is caused to emerge from the coil through the branch pipes thereof into the separating-vessel for further treatment.

2. In a centrifugal machine, a separating vessel or chamber contracted at its bottom to form a neck, in combination with a coil arranged at the greatest inner diameter, and provided with inwardly-projecting branch pipes, and having its discharging-orifice through the neck portion of the vessel, substantially as specified.

3. In a centrifugal machine, a separating-chamber mounted on a spindle, a supply-chamber arranged at the top of the separating-chamber and removably secured to an extension of the spindle, substantially as specified.

4. In a centrifugal machine, a separating-vessel contracted to form a neck, and provided with perforations in its bottom, in combination with a receiving-vessel arranged beneath the separating-vessel, and with a coil arranged in the separating-vessel above its neck, and provided with inwardly-projecting pipes, and having its discharge-orifice communicating with the receiving-vessel at the neck portion of the separating-vessel, substantially as specified.

5. In a centrifugal machine, the combina-

tion, with the separating chamber or vessel A and spindle Z O, and with the frame-work R, provided with a pair of pockets, of a bushing in each of the pockets, a lining in each of the 5 bushings, and a pulley loosely mounted on the upper lining and connected with the spindle by means of a pin projecting into a slot in said spindle, whereby lateral strain of the belt is borne by the bushings and linings, substantially as specified.

6. In a centrifugal machine, a separating chamber or vessel contracted at its bottom to form a neck having vertical walls, substantially as specified.

15 7. In a centrifugal machine for the continuous separation of compound fluids or semi-liquids, separating vessel A, provided with a coil

of tubing, T, having a number of pipes, T' T² T³ T⁴, therewith connected, outlet or mouth t³ at the bottom of said vessel, slots K' K² K³, 20 orifice k, and pipe k', also in the bottom thereof, in combination with a vessel, C, at the top of the separating-vessel, and a case, D, underneath said vessel, the case D provided with partition-plates D' D², having one or both a 25 groove or flange, d, in the extreme edge of said plates, and on which the liquids may be delivered, all substantially as shown and described.
